TOOTHBRUSH

Percy H. Hill, Winchester, and John G. Kreifeldt, Somerville, Mass., assignors to E. I. du Pont de Nemours & Company, Wilmington, Del.

Continuation-in-part of abandoned design applications Ser. No. 492,939, July 29, 1974, Ser. No. 574,353, May 5, 1975, and Ser. No. 601,072, Aug. 1, 1975. This application Oct. 3, 1975, Ser. No. 619,196

Term of patent 14 years

Int. Cl. D4—02

U.S. Cl. D4—25

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a top plan view of a first embodiment of a toothbrush showing our new design;

FIG. 2 is a side elevational view;

FIG. 3 is a bottom plan view; and

FIG. 4 is a back elevational view.

The side of the first embodiment not shown is a mirror image of the side shown in FIG. 2.

FIG. 5 is a top plan view of a second embodiment of a toothbrush showing our new design;

FIG. 6 is a side elevational view;

FIG. 7 is a bottom plan view; and

FIG. 8 is a back elevational view.

The side of the second embodiment not shown is a mirror image of the side shown in FIG. 6.

FIG. 9 is a top plan view of a third embodiment of a toothbrush showing our new design;

FIG. 10 is a side elevational view;

FIG. 11 is a bottom plan view; and

FIG. 12 is a back elevational view.

The side of the third embodiment not shown is a mirror image of the side shown in FIG. 10.

This application is a continuation-in-part of applications Ser. No. 492,939, filed July 29, 1974; Ser. No. 574,353, filed May 5, 1975 and Ser. No. 601,072, filed Aug. 1, 1975, all now abandoned.

We claim:

The ornamental design for a toothbrush, substantially as shown and described.
